(57) **CLAIM**

The ornamental design for terminal placement for a battery pack, as shown and described.

DESCRIPTION

FIG. 1 is a first perspective view of a battery pack with terminals according to a first embodiment.

FIG. 2 is a second perspective view of the battery pack with terminals of FIG. 1.

FIG. 3 is a left side view of the battery pack with terminals of FIG. 1.

FIG. 4 is a right side view of the battery pack with terminals of FIG. 1.

FIG. 5 is a front side view of the battery pack with terminals of FIG. 1.

FIG. 6 is a bottom side view of the battery pack with terminals of FIG. 1.

FIG. 7 is a first perspective view of a battery pack with terminals according to a second embodiment.

FIG. 8 is a second perspective view of the battery pack with terminals of FIG. 7.

FIG. 9 is a left side view of the battery pack with terminals of FIG. 7.

FIG. 10 is a right side view of the battery pack with terminals of FIG. 7.

FIG. 11 is a front side view of the battery pack with terminals of FIG. 7.

FIG. 12 is a bottom side view of the battery pack with terminals of FIG. 7.

(Continued)

FIG. 13 is a first perspective view of a battery pack with terminals according to a third embodiment.

FIG. 14 is a second perspective view of the battery pack with terminals of FIG. 13.

FIG. 15 is a left side view of the battery pack with terminals of FIG. 13.

FIG. 16 is a right side view of the battery pack with terminals of FIG. 13.

FIG. 17 is a front side view of the battery pack with terminals of FIG. 13.

FIG. 18 is a bottom side view of the battery pack with terminals of FIG. 13.

FIG. 19 is a first perspective view of a battery pack with terminals according to a fourth embodiment.

FIG. 20 is a second perspective view of the battery pack with terminals of FIG. 19.

FIG. 21 is a left side view of the battery pack with terminals of FIG. 19.

FIG. 22 is a right side view of the battery pack with terminals of FIG. 19.

FIG. 23 is a front side view of the battery pack with terminals of FIG. 19.

FIG. 24 is a bottom side view of the battery pack with terminals of FIG. 19.

FIG. 25 is a first perspective view of a battery pack with terminals according to a fifth embodiment.

FIG. 26 is a second perspective view of the battery pack with terminals of FIG. 25.

FIG. 27 is a left side view of the battery pack with terminals of FIG. 25.

FIG. 28 is a right side view of the battery pack with terminals of FIG. 25.

FIG. 29 is a front side view of the battery pack with terminals of FIG. 25.

FIG. 30 is a bottom side view of the battery pack with terminals of FIG. 25.

FIG. 31 is a first perspective view of a battery pack with terminals according to an sixth embodiment.

FIG. 32 is a second perspective view of the battery pack with terminals of FIG. 31.

FIG. 33 is a left side view of the battery pack with terminals of FIG. 31.

FIG. 34 is a right side view of the battery pack with terminals of FIG. 31.

FIG. 35 is a front side view of the battery pack with terminals of FIG. 31.

FIG. 36 is a bottom side view of the battery pack with terminals of FIG. 31.

FIG. 37 is a first perspective view of a battery pack with terminals according to a seventh embodiment.

FIG. 38 is a second perspective view of the battery pack with terminals of FIG. 37.

FIG. 39 is a left side view of the battery pack with terminals of FIG. 37.

FIG. 40 is a right side view of the battery pack with terminals of FIG. 37.

FIG. 41 is a front side view of the battery pack with terminals of FIG. 37.

FIG. 42 is a bottom side view of the battery pack with terminals of FIG. 37.

FIG. 43 is a first perspective view of a battery pack with terminals according to a eighth embodiment.

FIG. 44 is a second perspective view of the battery pack with terminals of FIG. 43.

FIG. 45 is a left side view of the battery pack with terminals of FIG. 43.

FIG. 46 is a right side view of the battery pack with terminals of FIG. 43.

FIG. 47 is a front side view of the battery pack with terminals of FIG. 43; and,

FIG. 48 is a bottom side view of the battery pack with terminals of FIG. 43.

The broken lines in the drawings illustrate features of the terminal placement for a battery pack that form no part of the claimed design.
